UNITED STATES PATENT OFFICE.

JOHN M. MERTZ, OF WILMINGTON, DELAWARE.

CARBURETOR TUBE.

Application filed November 28, 1923. Serial No. 677,465.

To all whom it may concern:

Be it known that I, JOHN M. MERTZ, a citizen of the United States, a resident of Wilmington, in the county of New Castle and State of Delaware, have invented a certain new and useful Carburetor Tube, of which the following is a specification.

The primary object of the invention is to provide a carburetor tube in which the area of the opening will be varied proportional to the speed of the engine, thereby automatically providing a larger amount of air, to compensate for increased fuel supply at higher velocities, when the engine is operating at higher speeds. A further object of the invention is to enable the above results to be brought about in a simple and effective manner, by the use of one or more spring members which form a Venturi throat in the carburetor tube, and are constructed to yield when the air velocity in the tube increases and thereby increase the area of the opening through which the air passes.

Further objects and advantages of the invention will be in part obvious and in part specifically pointed out in the description hereinafter contained, which, taken in connection with the accompanying drawings, discloses a preferred embodiment thereof; such embodiment, however, is to be considered as merely illustrative of its principles.

In the drawings:

Fig. 1 is a longitudinal sectional view of a carburetor tube constructed in accordance with the invention.

Fig. 2 is a transverse section taken on line 2-2 of Fig. 1.

In the drawings I have shown a carburetor tube 1 having suitable means for feeding fuel thereto, such as a nozzle 2 shown conventionally in Fig. 2, and which may be adjusted in any suitable manner, as by a needle valve 3. As the general construction of the carburetor and other parts associated with tube 1 are not essential to the present invention, they will not be described in detail herein.

The area of the opening in tube 1 through which the air passes past the needle valve 2 is determined by one or more spring members 4 which are somewhat bowed to form a Venturi throat in the tube adjacent needle valve 2, and the spring members 4 are made sufficiently resilient to flatten out upon increased air velocity within the tube, and

thus enlarge the cross-sectional area of the throat, permitting a relatively larger volume of air to be drawn into the cylinder with the fuel when the engine is operating at higher speeds.

The spring members 4 are also slidably supported at at least one end to permit them to flatten out as aforesaid; in the particular form of the invention illustrated, they are fixedly secured at one end to tube 1, as by rivets 5, while the other ends may slide along the walls of the tube when the springs flatten out as above described.

I also prefer to provide some device for adjusting the spring members 4, such as the thumb screws 6, which engage the free ends thereof.

In the present form of the invention the tube 1 is made of rectangular cross section, and two of the springs 4 are provided at opposite side walls thereof; but it will be understood that this arrangement is not essential either as regards the shape of the tube or the number of springs employed.

For accurate regulation the spring members 4 may be constructed to compensate for temperature differences which may occur at different seasons of the year, for example by constructing the springs in two pieces, with an outer layer 4^a of bronze, and an inner layer 4^b of steel or some other metal which expands relatively readily upon temperature increases.

The invention is also advantageous in that upon suddenly opening the butterfly valve or other volumetric air controlling device, there will be relatively little change in the mixture, due to the fact that the mixture remains practically constant at all air velocities instead of varying with the opening of the butterfly valve or other volumetric air controlling device.

While a specific embodiment of the invention has been disclosed, it will be obvious that many changes may be made therein without departing from its essential features as set forth in the appended claims.

I claim:

1. In combination, a nozzle, a carburetor tube surrounding the same, a spring member within said tube normally bowed to form a throat adjacent said nozzle, said spring member being sufficiently resilient to flatten upon increased air velocity within the tube and thus enlarge said throat, and being slidably supported to permit one end to move

freely when the spring flattens out as aforesaid.

- 5 2. In combination, a nozzle, a carburetor tube surrounding the same, a spring member within said tube normally bowed to form a throat adjacent said nozzle, said spring member being sufficiently resilient to flatten upon increased air velocity within the tube and thus enlarge said throat, said 10 spring member being fixedly secured in place adjacent one end and being slidably supported to permit the other end to move freely when the spring flattens out as aforesaid.
- 15 3. In combination, a nozzle, a carburetor tube surrounding the same, a spring member within said tube normally bowed to form a throat adjacent said nozzle, said spring member being sufficiently resilient to flatten 20 upon increased air velocity within the tube and thus enlarge said throat, and being slidably supported to permit one end to move

freely when the spring flattens out as aforesaid, together with means for adjusting the position of said spring member.

- 25 4. In combination, a nozzle, a carburetor tube surrounding the same, a spring member within said tube normally bowed to form a throat adjacent said nozzle, said spring member being sufficiently resilient to flatten 30 upon increased air velocity within the tube and thus enlarge said throat, said spring member being fixedly secured in place adjacent one end and being slidably supported to permit the other end to move 35 freely when the spring flattens out as aforesaid, together with means engaging said last-mentioned end of the spring member for adjusting the position thereof.

40 In testimony that I claim the foregoing, I have hereunto set my hand this 24th day of November, 1923.

JOHN M. MERTZ.
